YARN WINDING

George M. Karns, Swarthmore, Pa., assignor to
E. I. du Pont de Nemours & Company, Wil-
mington, Del., a corporation of Delaware

Application December 30, 1941, Serial No. 424,845

11 Claims. (Cl. 28—32)

This invention relates to yarn winding, and more particularly it relates to a new and improved method and apparatus for the beaming of yarn, and to a new and improved beamed package of yarn.

The beaming of yarn is common practice in the textile industry, and comprises the simultaneous winding of a large number of yarns (100 to 500 or more yarns) in parallel, side-by-side relationship on to a yarn support commonly referred to as a beam. Such beam packages of yarn are conventionally used in the weaving industry where the many parallel yarns, when unwound from the beam, serve as the warp threads in a weaving operation. Beam packages of yarn are also used in the shipment of yarns to tire cord manufacturers, the latter simultaneously unwinding the yarns and plying and twisting two or more of the yarns in the formation of strands and cords at a plurality of plying and twisting positions.

In the beaming of yarns sufficient tension (of the order of 25 to 100 grams) is imposed on the yarns during the winding operation to maintain them in the desired parallel arrangement and insure their proper positioning along the length of the beam package. Occasionally, when the yarn sheet being wound on to the beam contains too few yarns to completely fill the length of the beam, the sheet is traversed along the beam surface. This traverse stroke is relatively short, however, and even in the case of a 52-inch beam, it rarely exceeds $\frac{1}{8}$ of an inch. Thus, even in an extreme case, the yarns are wound on the beam in a substantially parallel ribbon wind manner and the fully wound package is substantially free of helical crossings of the sheet.

Prior to the present invention, it was considered necessary to bind together the filaments of continuous filament artificial yarns before the latter could be satisfactorily beamed. Such binding of the filaments was carried out by imparting a twist of at least 4 or 5 turns per inch to the yarn, or by sizing the yarn and forming the same into a bundle of substantially circular cross-section in the manner set forth in the United States patent to Bradshaw and Standley No. 2,224,665.

Obviously, if the individual yarns wound into a beam package possess no twist, and if the filaments are not otherwise bound together, there will be no sharp line of demarcation between the various filament bundles constituting the several individual yarns. The individuality of each separate yarn must be maintained solely by the con-

tinuity of all of the filaments contained therein. If one or more single filaments are broken from such an untwisted yarn bundle, there will be no force exerted on these filaments to hold them to that bundle and cause them to unwind with it from the beam package in the usual manner; they will more probably cling to the beam package and wrap about it. This wrapping of broken filaments not only affects the individual yarn from which the filaments are broken, but also tends to abrade adjacent yarns contained on the beam and break individual filaments loose from them as well. Moreover, if such an untwisted yarn, wound into a beam package should be completely broken, the fact that neither this yarn nor those adjacent it possess any twist makes it extremely difficult if not impossible to later locate that broken end in the package. In fact, it is possible that the filaments comprising that yarn may become associated with the filaments of adjacent yarns so that it is practically impossible to later completely reassemble this broken yarn end. Obviously, such a situation detracts greatly from whatever advantages a beam package of untwisted continuous filament yarns may otherwise possess.

It is, therefore, an object of the present invention to produce a beamed package of yarns which may be unwound without entanglement of adjacent yarns, or filaments of adjacent yarns, even though such yarns or filaments are broken, and even though the filaments of the individual yarns are not bound together.

It is also an object of the present invention to provide a method and apparatus for winding a beamed package of yarns which may be unwound without entanglement of adjacent yarns, or filaments of adjacent yarns, regardless of whether such yarns or filaments become broken during the winding operation.

Other objects of the invention will appear hereinafter.

The objects of this invention are accomplished, in general, by simultaneously winding, on to a beam, a plurality of parallel, untwisted yarn ends and, at the same time, traversing a single thread of suitable strength back and forth along the entire length of the beam package so as to lie between, and separate, successive layers of the sheet of parallel, untwisted, beamed yarns. Later, during the unwinding operation, this single traverse thread will be unwound from the beam package at the same time as the parallel, untwisted yarns are unwound, the single

thread being collected on a separate yarn support, such as a pirn, bobbin or spool.

The traverse thread of this invention acts in the following manner to aid the unwinding operation. So long as the sheet of yarn is coming from the beam in a normal and satisfactory manner, the traverse thread will be unwound from on top of each successive layer of yarn and will have no effect on these yarns or on the unwinding operation. However, if one or more filaments break and become separated from their respective yarn bundles and wrap about the beam, the traverse thread will be positioned under that wrap and will break it during the unwinding operation. Those lengths of the filaments forming the wrap will then be carried by the traverse thread from the beam to a point where they can do no harm to either their own or adjacent yarn bundles. Thus, the traverse thread of this invention will prevent the formation of dangerous filament wraps during the unwinding operation. Or, if an entire yarn should break, the traverse thread will act in a similar manner to prevent that yarn from wrapping itself about the beam.

Most beaming equipment in use today is provided with suitable stop motion devices that operate to stop the unwinding operation in case such an entire yarn breaks. Thus, there is little likelihood that a completely broken yarn will wrap itself about the beam without stopping the winding operation. Nevertheless, the traverse thread of the present invention still aids importantly in the event of such a break. As has already been mentioned, when an untwisted continuous filament yarn contained in a beam package breaks, the free ends of the individual filaments comprising that yarn tend to cling to adjacent or underlying yarns and associate themselves therewith so that it is difficult if not impossible to reassemble all those broken filaments into the form of their original bundle and proceed with the unwinding operation. The present invention overcomes this difficulty, however, inasmuch as the traverse thread makes it possible to lift from the beam package all the yarn contained in the outer sheet layer. When this is done, the filaments of the broken yarn (also lifted free of the beam) can be readily observed and gathered together into their proper yarn bundle. Thus, the present invention also makes it possible to locate and reassemble a broken yarn contained in a beam package.

The details of the present invention will be more readily understood by reference to the following detailed description, when taken in connection with the accompanying drawings, in which:

Figure 1 is a diagrammatic perspective view showing apparatus suitable for use in accordance with the present invention.

Figure 2 is a diagrammatic side elevational view of the device shown in Figure 1.

Figure 3 is a front elevational view showing the essential features of the device of Figure 1 and detailed means for operating the same.

Figure 4 illustrates a modified form of yarn traversing mechanism suitable for use in accordance with the present invention.

Figure 5 is an enlarged detailed view showing the manner in which the traversing yarn is positioned between layers of the beamed yarn.

Figure 6 is a diagrammatic side elevational view showing one form of apparatus for use in unwinding the beamed yarn.

Figure 7 is a diagrammatic side elevational

view showing a modified form of apparatus for the unwinding of the traversing yarn.

Referring to Figures 1 and 2 of the drawings, reference numeral 11 designates a beamed yarn package, the beam being provided with flanges 13 and 15 and operating shaft 17. A plurality of yarns 19, from any desired source such as a bank of small yarn packages, is simultaneously wound on to the beam package 11 in parallel, side-by-side relationship as illustrated. The plurality of yarns 19 is maintained in proper spaced relationship by means of comb guide 21. A package of wound yarn 23 is positioned below the continuous sheet of yarns 19. A yarn guide 27 is positioned above yarn package 23 and the yarn 25 is passed from the package 23 through guide 27 then through traversing guide 29 and on to the beam package immediately under the sheet of yarns 19 as the latter contacts the beamed package 11. The traverse guide 29 is traversed by means of traverse bar 31 which may be reciprocated by hand or by any desired mechanical device. Preferably, the yarn passes over a straight edge of a bail or plate 33. This functions to position the yarn on the beam package more evenly. The traverse bar 31 and guide 29 are reciprocated longitudinally of the beam as yarn 25 and the beam yarns 19 are wound on to the package.

Referring to Figure 3 of the drawings, in which parts which are the same as those shown in Figures 1 and 2 are designated by like reference characters, the traverse bar 31 is reciprocated by means of grooved cam 41. A groove following pin 45 positioned on the end of bar 31 rides in the groove 43 of the grooved cam 41. Upon rotation of the cam by means of motor 47, shaft 48 and sprocket chain 49, the pin 45 moves back and forth across the face of the cam thereby causing yarn guide 29 to reciprocate across the face of the beam 11. The beam 11 may be rotated by means of the same motor 47 by connecting a sprocket chain 51 between beam shaft 17 and cam shaft 48.

Referring to Figure 4 of the drawings, which again shows like parts by like reference characters, two thread guides 29 are mounted on individual sleeves 61 which are adapted to slide back and forth across fixed bar 63. A cam 65, containing two cam grooves 67 in side-by-side relationship is positioned adjacent bar 63. Each sleeve 61 is provided with a cam groove following pin 69 which is adapted to ride in a groove 67 of cam 65. The cam 65 is rotated by means of cam shaft 66 through gears 71 and 73 which are driven by motor 47. As the cam 65 rotates, the sleeves 61 and yarn guides 29 are slid back and forth longitudinally of the beam on the fixed bar 63. Each sleeve is traversed one-half the distance across the beam 11 and two yarns 25 are thereby positioned under the sheet of beamed yarns 19, as shown. If desired, the beam 11 may be driven by connecting the cam shaft 66 with the beam shaft 17 by means of a sprocket chain 75 or the like. By connecting the beam and the cam a synchronized movement of the traverse yarns with the beamed yarns will be obtained.

Figure 5 of the drawings illustrates in an enlarged detailed section how the traverse yarn 25 will lie between layers 26 of the beamed yarn.

Figure 6 of the drawings illustrates means for unwinding the beamed yarns together with traverse yarn from the beamed package. The beamed yarns will, of course, be unwound in the conventional manner. It is necessary, however, that

the traverse yarn 25 be unwound at substantially the same rate as the beamed yarns. If the pull on the traverse yarn is too great, it will cause this yarn to be pulled from between layers of the beamed yarn on the beamed package. Such a withdrawing of the traverse yarn from between layers of the beamed yarn may cause abrasion of the filaments of the beamed yarn. On the other hand, if the traverse yarn 25 is collected at a lower speed than the unwinding of the beamed yarns, there is danger of entanglement between the traverse yarn and the beamed yarn. In the device shown in Figure 6, the traverse yarn is passed through fixed guides 81 and 83, the latter being positioned substantially above a pirl 85 positioned in a ring twisting device. The yarn 25 is passed to the pirl and is wound thereon with that tension imparted thereto by the ballooning of the yarn passing to the follower 86 of the ring twisting device. The pull on the yarn will always be the same and the beamed yarns 19 may be withdrawn from the beam at varying speeds without substantially varying the tension on the traverse yarn 25.

Referring to the apparatus shown in Figure 7, the traverse yarn 25 is passed from the beamed package through guide 87 to a flanged spool 89 which is driven by rotating shaft 91 through ball bearings 93. The slight friction between the shaft 91 and the ball bearings and between the ball bearings and the flanged spool 89 will be sufficient to impart a slight tension to traverse yarn 25. The tension on traverse yarn 25 will be sufficient to continue to unwind the same as the beamed yarns are being unwound but will be insufficient to drag the yarn from between layers of the beamed yarn on the beamed package.

It will be obvious to anyone skilled in the art that numerous other devices for unwinding the traverse yarn simultaneously with the beamed yarns can be employed. For example, the traverse yarn 25 may be withdrawn by hand, or even on a positively driven spool, the rotational speed of which is synchronized with the rotational speed of the beam.

The speed of traverse of traverse yarn 25 may vary greatly in accordance with the type and structure of the beamed yarns. In general, it is preferred that the traverse yarn is traversed a distance at least equal to the length of the beam for each complete rotation of the beam. In the case of yarns comprising continuous artificial filaments having no twist, it is found desirable to traverse the traverse yarn at a speed equal to two lengths of the beam for each complete revolution of the beam. Again, if the beam is of large diameter, it may be desirable to gradually increase the speed of the traverse guide so that the length of the sheet of beamed yarns wound on the beam between successive crossings of the traverse threads will remain approximately the same. The speed of traverse of the traverse yarn will also depend somewhat upon the strength of the traverse yarn; the traversing of the thread can be much slower relative to the rotational speed of the beam if the traverse thread is quite strong.

Although it is usually preferred to traverse the traverse yarn from one extreme end to the opposite extreme end of the beam, there may be instances where difficulty from entangled filaments and yarns is only experienced over the central portion of the beam, or some other section of the beam. Under these conditions, of course,

it will not be necessary to traverse the traverse yarn across the whole length of the beam.

The traverse thread may be composed of any desired material, for example, cotton, linen, silk, nylon, or other natural or artificial materials. Preferably, the traverse yarn is constructed from continuous filaments which have considerable strength such as nylon or silk. The traverse yarn is preferably of small diameter with a medium to high twist.

10 The method provided by the present invention was devised for use in connection with the winding of a plurality of continuous filament yarns possessing substantially no twist on to a beam package and it naturally finds its greatest utility in such instances. It makes the formation and subsequent unwinding of such packages entirely feasible from the standpoint of both yarn quality and ease of operation. When used in connection with the sizing and yarn shaping treatment provided by U. S. Patent No. 2,224,665 to Bradshaw and Standley, the beam package obtained may be unwound with almost complete freedom from yarn breaks and wraps.

15 Although it finds its most important use in connection with the winding of untwisted yarns on to a beam package, the invention is not so limited. It may also be used to advantage in the beaming of twisted yarns since it provides a positive method of removing from the beam package any broken yarn ends or loose filaments that may occasionally form in such package whether it contains untwisted or twisted yarns.

20 Yarn beamed in accordance with the present invention may be readily and smoothly unwound without entanglement of filaments or yarns. The method of beaming yarns of the present invention may be employed even when the filaments are untwisted and free from size binding the filaments together. In cases where an individual filament has become broken from the remainder of its yarn bundle, the invention operates to lift that filament from the beam package and carry it to a point where it can do no harm to other yarns contained in the package.

25 35 The invention provides means whereby a broken yarn end can be readily located on a beamed package of untwisted continuous filament yarns.

40 45 The method and apparatus of the present invention are simple in construction and economical to operate. Furthermore, the apparatus can be readily installed on existing types of beaming equipment.

50 55 Since it is obvious that many changes and modifications can be made in the above-described details without departing from the nature and spirit of the invention, it is to be understood that the invention is not to be limited to the details described herein except as set forth in the appended claims.

60 I claim:

65 1. A beam package of yarn comprising a plurality of yarns wound in parallel, side-by-side relationship without substantial traverse, and a single yarn wound with a traverse from end to end of said package between layers of said plurality of yarns, said single yarn readily withdrawable in the subsequent unwinding of said plurality of yarns to prevent objectionable entanglements of filaments.

70 75 2. A beam package of yarn as defined in claim 1 in which the said single yarn is wound with a traverse of at least the length of said package for each circumferential layer of said plurality of yarns.

3. A beam package of yarn as defined in claim 1 in which said plurality of yarns is composed of continuous filaments.

4. A beam package of yarn as defined in claim 1 in which said plurality of yarns is composed of continuous, unbound filaments.

5. In the winding of a plurality of yarns in parallel, side-by-side relationship on to a beam, the step of simultaneously winding a single yarn, with a traverse from end to end of said beam, between layers of said plurality of yarns, said single yarn readily withdrawable in the subsequent unwinding of said plurality of yarns to prevent objectionable entanglement of filaments.

6. In the winding of a plurality of yarns in parallel, side-by-side relationship onto a beam, the step of simultaneously winding a single yarn, with a traverse from end to end of said beam, between layers of said plurality of yarns, the speed of traverse of said single yarn being at least equal to the length of the beam for each revolution of said beam.

7. In the winding of a plurality of yarns in parallel, side-by-side relationship onto a beam, the step of simultaneously winding a single yarn, with a traverse from end to end of said beam, between layers of said plurality of yarns, the speed of traverse of said single yarn being approximately equal to twice the length of said beam for each revolution of said beam.

8. A beaming apparatus comprising a rotatable beam, means for guiding a plurality of yarns in

parallel, side-by-side relationship on to said beam, a yarn guide spaced from said means for guiding a single yarn on to said beam, and means for reciprocating said yarn guide from end to end of said beam.

9. The process which comprises winding a plurality of yarns in parallel side-by-side relationship on to a beam, winding another yarn with a substantial traverse longitudinally of said beam between layers of said plurality of yarns, unwinding all of said yarns from said beam, said other yarn being maintained under tension and passed to a separate individual destination during the unwinding thereof, whereby said plurality of parallel yarns may be unwound without entanglement of adjacent yarns and filaments.

10. The method of preventing objectionable entanglement of adjacent yarns and yarn filaments in the unwinding of beamed yarns which comprises withdrawing, under tension and to a separate destination, a yarn wound with a substantial traverse between layers of said beamed

20 25 30

11. The method of preventing objectionable entanglement of adjacent yarns and yarn filaments in the unwinding of beamed yarns which comprises withdrawing, under tension and at a linear speed in excess of that of the unwinding of the beamed yarns, a yarn wound with a substantial traverse between layers of said beamed

yarns.

GEORGE M. KARNS.
